UNITED STATES PATENT OFFICE.

EUGENE DE KLEIST, OF NORTH TONAWANDA, NEW YORK.

COIN-CONTROLLED MACHINE.

SPECIFICATION forming part of Letters Patent No. 723,878, dated March 31, 1903.

Application filed March 3, 1902. Serial No. 96,519. (No model.)

To all whom it may concern:

Be it known that I, EUGENE DE KLEIST, a citizen of the United States, residing at North Tonawanda, in the county of Niagara and State of New York, have invented new and useful Improvements in Coin-Controlled Machines, of which the following is a specification.

This invention relates to the intercepting or detaining devices employed in coin-controlled machines of various kinds for preventing the discharge of the deposited coin for a predetermined period in order to cause the machine to perform a certain operation or a series of operations for every deposit of a coin before coming to a standstill.

My invention has more particular reference to coin-intercepting devices having terminals with which the deposited coin coöperates to close an electric circuit containing a motor for driving the movable parts of the machine—such, for instance, as the rotary pin-barrel of an automatic musical instrument.

The object of my invention is to provide a reliable intercepting and controlling device of simple construction which insures the discharge of the intercepted coin after the machine has delivered the intended equivalent of value—such as an article of merchandise, the playing of a tune, &c.—thus baffling fraudulent attempts to repeat or improperly prolong the operation of the machine by the deposit of a single coin or token.

In the accompanying drawings, Figure 1 is a fragmentary transverse vertical section of a self-playing piano containing my invention. Fig. 2 is a similar section taken through the coin-chute. Fig. 3 is a fragmentary horizontal section in line 33, Fig. 1. Fig. 4 is a vertical section of the discharge-hopper of the chute on an enlarged scale. Fig. 5 is a similar section at right angles to Fig. 4. Fig. 6 is a bottom plan view of said hopper. Fig. 7 is a horizontal section in line 77, Fig. 1. Fig. 8 is a fragmentary vertical section in line 88, Fig. 7.

Like letters of reference refer to like parts in the several figures.

My improvement is herein shown as applied to an automatic piano in which the sound-producing parts and the discharge of the in-

tercepted coin are controlled by a rotary pin-barrel, which is driven by an electric motor. The invention is, however, also applicable to various other coin-controlled machines and is shown in connection with such a piano only by way of illustration.

Referring to the drawings, A indicates the upper portion of the case of an automatic piano of the kind in which the hammers of the action are indirectly operated from a rotary pin-barrel B. The piano-action, the sound-producing members, and the driving mechanism of the barrel are not shown in the drawings and may be of any ordinary construction.

C indicates a coin-chute arranged in the contracted upper portion D of the piano-case and extending at its upper end through the front wall of the case. The open lower end 70 of the chute is arranged over a discharge hopper or throat C', which receives the coins from the chute. This hopper, although preferably disconnected from the chute, is practically an extension thereof. The two opposing side walls d d of the hopper which face the edge of the deposited coin or token are stationary and converged downwardly at such an angle as to form a discharge-throat between them, which is narrower than the 80 diameter of a proper coin, by which construction the deposited coin is arrested by bearing at its edge against said converging walls, as shown by dotted lines in Fig. 5. One of the other walls of the discharge-hopper—say the wall d'—is provided with or constructed in the form of a discharge-gate adapted to be moved to a position in which it leaves a delivery-passage through which the arrested coin may be ejected by a suitable 90 ejector which enters the hopper through the opposite wall d² of the hopper. In the construction shown in the drawings the wall d' is pivoted between its ends to the side walls d by a horizontal pin e, so that its lower portion may swing outwardly beyond the side walls for forming a discharge-opening for the coins, as shown by dotted lines in Fig. 4, or inwardly between the side walls for closing said opening, as shown by full lines in that 100 figure.

f indicates the coin-ejector, which prefer-

ably consists of a yoke-shaped piece of wire secured at one end to the lower portion of the gate or movable wall d' and extending around one side of the hopper to a point opposite the gate, where it terminates in a finger f' . This finger faces the gate and is adapted to enter the passage of the chute through an opening f^2 , formed in the adjacent wall d^2 , as shown in Figs. 4, 5, and 6. The finger f' normally 10 clears the coin-passage, as shown by full lines in Figs. 4 and 6; but when the gate d' is opened it is caused to follow the gate and move across the coin-passage at a point in line with the arrested coin, as shown by dotted lines in Fig. 4, thereby pushing the coin sideways beyond the side walls and discharging it from the hopper through the opening left between said walls and the open gate. From the hopper the coin drops into a chute 20 C^2 , leading to a suitable receptacle, which is not shown in the drawings.

To prevent the gate from swinging inwardly far enough to obstruct the coin-chute, the same is provided at its edges with stops f^3 , 25 which strike the edges of the adjacent hopper-walls.

When my improved intercepting and ejecting device is employed for controlling the action of an electric motor which drives the 30 movable parts of the machine, the side walls d of the coin discharge throat or hopper, against which the edge of the coin bears, are made of metal and utilized as the terminals of the electric circuit G , in which the motor g is 35 included, the deposited coin forming a bridge or plug which temporarily connects these terminals and closes the circuit. The terminal walls d are insulated from each other by the other two walls, which latter are made of hard 40 rubber or other suitable material.

The discharge-gate d' may be opened by any suitable controlling device; but I prefer to employ for this purpose the automatic mechanism shown in the drawings, which is 45 constructed as follows: H indicates an upright actuating-wheel arranged in the case A at one side of the discharge-hopper C' and mounted on a horizontal stud or shaft h , supported in a standard h' . This wheel is provided on one side with an annular row of feed-pins h^2 and on its other side with a similar row of pins or tappets h^3 . An intermittent rotary motion is imparted to this wheel by a feed-pawl i , which is mounted on a vertically-swinging rock-lever J and which engages with the feed-pins h^2 of the wheel. The feed-pawl is pivoted by a horizontal pin i^2 to the front arm of the rock-lever J and held rigid during its forward stroke by a stoppin i^3 on said lever, but is free to yield and ride over the pins of the wheel during its return stroke. The rock-lever J is actuated by a vertically-swinging finger K , with which its rear arm is connected by a rod k and which 60 is in turn tripped by a tooth or tappet l on the pin-barrel B . This finger is carried by a 65

cross-bar M . By this mechanism the actuating-wheel is turned the distance of one of its feed-pins during every rotation of the pin-barrel.

N is a horizontally-swinging lever pivoted at n to the standard h' and connected at one end with the upper end of the gate d' by a rod o and provided at its opposite end with a projection o' , which is arranged in the path of 70 the tappet-pins of the actuating-wheel H , as shown in Fig. 1, whereby the lever is tripped by said pins and swung in the proper direction to open the gate. As shown in the drawings, the projection o' preferably consists of 80 a screw which can be adjusted vertically on the lever to cause its lower end to extend a greater or less distance below the tappet-pins of the actuating-wheel, and thereby regulate the stroke of the lever and the gate d' accordingly.

A spring p , which connects the lever N with a fixed part p' , serves to swing the lever in the reverse direction for closing the gate. Backward movement of the actuating-wheel H is 90 prevented by a suitable detent-pawl q .

In the normal position of the parts the coin-discharge gate d' is closed and the insulated terminal walls d of the discharge-hopper are electrically disconnected, leaving the motor-circuit open. Upon depositing a coin in the chute the same drops until it is arrested by its edge striking the converging terminal walls d , as shown by dotted lines in Fig. 5. The coin thus bridges these walls and closes the 100 motor-circuit, causing the pin-barrel B to be turned and operating the instrument. When the barrel has made a complete turn, its projection l trips the rock-finger K , causing the actuating-wheel H to be turned the distance 105 of one of its feed-pins through the medium of the rock-lever J and feed-pawl i . When by the rotation of the actuating-wheel one of its tappets h^3 rocks the horizontal lever N , the gate d' is opened and the coin thrust laterally out of the hopper by the ejector f , as hereinbefore described, thereby breaking the motor-circuit and stopping the instrument. By providing the actuating-wheel H with as many tappets h^3 as it has feed-pins h^2 the gate 115 is opened once for every turn of the pin-barrel C and the instrument plays the tune once for each deposit of a coin. By providing the actuating-wheel with half as many tappets as feed-pins, as shown in the drawings, the barrel will make two turns and cause the tune to be played twice before ejecting the coin and stopping the machine, the instrument in this manner playing the tune a greater or less number of times for each deposit of a coin, 120 according to the ratio between the number of feed and tappet pins.

Among the practices resorted to for defrauding coin-controlled machines is that of applying an adhesive substance to the coin, as 130 chewing-gum, to cause the same to stick in the coin-chute, thus preventing the discharge

of the coin and enabling the machine to be operated repeatedly. This practice is foiled by my improved ejecting device, because the ejector is positively operated by the discharge-gate d' , and the latter is positively opened by the pin-barrel and intermediate mechanism.

In order to prevent operation of the machine by an undersized coin, the lower end of the throat or hopper C' is made so large that it will not arrest such a coin.

In order to prevent the hopper C' from being clogged by depositing several coins at a time or in quick succession and so causing the instrument to play for an indefinite period, the coin-chute C is provided above the discharge-hopper C' with a by-pass or branch chute R and an automatic switch or baffle-door R' , located at the junction of said main and branch chutes. This switch is controlled by the actuating mechanism of the instrument in such a manner that it clears the passage of the main chute C and permits the descent of a deposited coin when the instrument is at rest, but is automatically moved across said chute as soon as the instrument is set in motion by the deposit of a coin, thus directing any additional coins deposited while the instrument is still playing into the branch chute, where they cannot affect the instrument. In the construction shown in the drawings the switch R' is secured at its lower end to a horizontal rock-shaft r , journaled at the junction of the main chute with the lower side of the branch chute R and having an arm r' , which is connected with the movable board of a motor-bellows or pneumatic S by an eyebolt r^2 or other connection, as shown in Figs. 7 and 8. This bellows is normally expanded by a spring s and constantly communicates with the exhaust or wind chest T of the instrument by a tube or conduit t . By this construction when the instrument is at rest the bellows S is relieved from suction and the switch or baffle-door R' is held in the open position (shown by full lines in Fig. 2) by the expanded bellows. Upon depositing a proper coin in the main chute C the instrument is set in motion, causing the air to be exhausted from the wind-chest T in a well-known manner. The bellows S is thereby collapsed and caused to swing the switch into the closed position, (shown by dotted lines in Fig. 2,) deflecting any additional coins into the branch chute R as long as the instrument remains in operation and defeating any attempt to defraud the machine by obstructing the discharge-hopper C' . The branch chute R may discharge into the chute C^2 . As soon as the instrument ceases to play the bellows S is again allowed to expand, returning the coin-switch to its normal open position.

I claim as my invention—

1. In a coin-controlled machine, a coin-chute having a pair of opposing rigid walls separated by a throat which is narrower than the diameter of a proper coin, whereby the

descending coin is arrested by bearing edge-wise against both of said walls, a discharge-opening arranged in one of the remaining walls of the chute, and a coin-ejector arranged to move across said throat opposite said discharge-opening, substantially as set forth. 70

2. In a coin-controlled machine, a coin-chute having a pair of opposing rigid walls separated by a throat which is narrower than the diameter of a proper coin, whereby the descending coin is arrested by bearing edge-wise against both of said walls, a discharge-opening arranged in one of the remaining walls of the chute, a gate which normally closes said opening, and a coin-ejector arranged to pass through the wall of the chute opposite said gate and movable across said throat, substantially as set forth. 75

3. In a coin-controlled machine, the combination of an electric circuit, a coin-chute having a pair of rigid, opposing walls of metal forming terminals of said circuit and separated by a throat which is narrower than the diameter of a proper coin, an ejector arranged to pass through one of the remaining walls of the chute and movable across said throat, a discharge-opening arranged in the wall of the chute opposite said ejector, and a gate normally closing said opening and operatively connected with said ejector, substantially as set forth. 80

4. The combination of a coin-chute having two of its opposing walls separated by a throat which is narrower than the diameter of a proper coin and having one of its remaining walls pivoted to swing toward and from the opposing wall, an ejector arranged to enter the chute through the wall opposite said pivoted wall and operatively connected with the latter, and means for operating said pivoted wall, substantially as set forth. 85

5. The combination of a coin-chute having two of its opposing walls separated by a throat which is narrower than the diameter of a proper coin and having one of its remaining walls provided with a pivoted coin-discharge gate, and an ejector consisting of a yoke carried by said gate and extending around the side of the hopper and provided with a finger 115 which is arranged to enter the chute through an opening in the wall located opposite said gate, substantially as set forth. 110

6. In a coin-controlled machine having a pneumatic-actuating mechanism, the combination of a wind-chest, a coin-chute having an auxiliary channel or branch chute, a coin-switch arranged at the junction of said main and branch chutes, and a shifting bellows for said switch connected with said wind-chest, 120 substantially as set forth. 125

7. In a coin-controlled machine, having a pneumatic-actuating mechanism, the combination of a wind-chest, a coin-chute having an auxiliary channel or branch chute, a rock-shaft journaled at the junction of said main and auxiliary chutes and having an actuat- 130

ing-arm, a coin-switch carried by said rock-shaft and arranged to clear or obstruct said main chute, and a bellows communicating with said wind-chest and having its movable board connected with the arm of said rock-shaft and provided with an expansion-spring, substantially as set forth.

Witness my hand this 27th day of February, 1902.
